UNITED STATES PATENT OFFICE.

JOHN W. HARMON, OF BOSTON, MASSACHUSETTS.

ARTIFICER'S LEVEL.

SPECIFICATION forming part of Letters Patent No. 270,951, dated January 23, 1883.

Application filed January 23, 1882. (No model.)

To all whom it may concern:

Be it known that I, JOHN W. HARMON, of Boston, of the county of Suffolk and State of Massachusetts, have invented a new and useful Improvement in Artificers' Levels; and I do hereby declare the same to be described in the following specification and represented in the accompanying drawings, of which—

Figure 1 is a side elevation, Fig. 2 a longitudinal section, and Fig. 3 an end view, of the instrument embracing my invention, which has reference to the leveling-instrument for which Letters Patent No. 234,709, dated November 23, 1880, have been granted to me.

My present invention is defined in the claims hereinafter presented; and it consists mainly in the combination of a stand provided with a circular flange, divided arc, central pivot, centralizing-pointer, and adjustable legs, with a bar having lips and a pivotal screw, and with the spirit-level-carrying bar, arched standard, telescope, and adjusting-screws, all being substantially as hereinafter described and as represented. The aforesaid bar, pivoted at its middle to the instrument-base, serves, when off the stand, to connect the said base to a wooden or other proper bar and as a medium for the base adjusting screws to work against. It also answers as a slope or batter definer, as by means of it and the smaller spirit-level of the instrument the batter of a wall or chimney may be defined or ascertained; so by means of it and the large spirit-level a slope may be defined or determined, all of which will be readily understood by artificers or persons who may have occasion to use the instrument.

My invention further consists in a circular stand provided with a divided arc, a pivot-centralizing pointer, and adjustable legs, combined or for use with such leveling-instrument, or with it and the said base-bar, as hereinafter set forth.

In the drawings, A denotes the instrument-base, it being straight on its bottom or lower edge. There projects up from such base an arched standard or level-guard, B, it being formed and arranged as shown. Within the base is a spirit-level, C, the former being troughed or chambered to receive the latter and provided with a cap-plate, E, to cover it. This cap-plate has a slot, a, in it over the level,

to render visible the air-bubble of the latter. Furthermore, the base is provided with two projections, F F, one of which is adapted to receive another spirit-level, G, which is arranged at a right angle to the level first named, there being in the side of the socketed projection an opening or slot, b, to admit of the air-bubble of the level G being seen, as occasion may require. There is pivoted to the standard B at its crown or middle part a socket-piece, H, to receive and support a telescope or sight-tube, I, which extends through the socket-piece, and is held in place therein by means of a clamp-screw, c, screwed into the socket-piece and against the tube. The said telescope or sight-tube rests upon the milled heads of two adjusting-screws, K K, which are screwed into the projections at the ends of the arched standard, and arranged therein and with relation to the tube and its socket-piece in manner as represented. These screws serve to properly adjust the telescope or sight-tube with reference to either of the spirit-levels, and especially to bring it into parallelism with the lower surface of the base, which is to be supposed to be arranged in parallelism with the axis of the spirit-level C, covered and protected by the arched standard.

I would remark that the telescope or sight-tube may be pivoted at its middle directly to the crown of the arched standard; but it is preferable to have it applied thereto by means of the separate socket-piece, as described, arranged with and adapted to the standard in manner as explained.

Besides the screws K, the instrument may be provided with one or more adjusting-screws, N, arranged in its base in manner as represented, such being to enable the base to be brought into a horizontal plane when resting on a surface somewhat inclined thereto.

The telescope or sight-tube I provide with a proper fore sight or crossed wires diametrically arranged in it at right angles to each other, 95 they being shown at h. The tube also has a suitable back sight or eye-piece, k.

I do not herein claim the combination of the straight-edged base, the spirit-levels, their arched guard, and the telescope pivoted to such guard, and with the base provided with adjusting-screws arranged in the base and be-

neath the telescope, such being as represented in the aforesaid patent granted to me.

At its middle the base A extends between two lips or standards, *g*, that project upward from a flat metallic bar, *O*, a pivotal screw, *P*, being inserted in such lips and base, as represented, whereby the bar *O* is pivoted or hinged to the base *A*. The said bar *O* extends a suitable distance beyond the base *A* at each end thereof, and has in it holes *f* to receive screws for fastening the said bar to a common artificer's level or to a beam or bar, as occasion may require. The screws *N*, at their lower ends, bear on the bar *O*. Furthermore, the base *A* and the bar *O* have at the centers of their lower surfaces holes *l m*, respectively, for reception of a pivot, *n*, projecting upward from the center of a circular stand, *R*, provided with legs *S S S*, each of which is a screw screwed upward into the stand, these legs being at equal distances apart. Extending downward from the stand *R* is a centralizing-pointer, *T*. The periphery of the stand has marked upon it the divisions of an arc of ninety degrees of a circle, as shown at *U*. This stand may be used with the leveling-instrument either with or without the bar *O* applied to the said instrument, the pointer serving to centralize the stand over any point in a surface on which the legs of the stand may rest. With the stand not only can the instrument be used for determining angles, but it can be leveled so as to turn or traverse around in a horizontal or an inclined plane, all of which will be readily understood by artificers. The stand has at its periphery a circular flange, *x*, projecting up from it, as shown, such flange being to support the bar *O* when pivoted to the stand.

In using the centralizing-pointer it is to

have its point or lower end brought directly over and upon the point constituting the vertex of an angle set off or measured by the graduated stand. The pointer thus becomes a pivot or guide to keep the stand in position, while it may be revolved to bring the telescope (with the bar or standard set to the commencement of the scale) to bear upon an object the angle between which and another is to be measured or set off. The stand next being leveled and the telescope properly ranged on the object, such telescope may be turned horizontally to the angle to be set off or to bear on the object whose angle with the first-named object is to be ascertained.

An artificer's level constructed as described becomes a convenient, cheap, and durable article for use by masons, joiners, or machinists for leveling. It can also be used for defining inclinations or slopes.

What I claim as my invention is as follows, viz:

1. The combination of the stand *R*, provided with the circular flange, divided arc, central pivot, centralizing-pointer, and adjustable legs, with the bar *O*, provided with the lips *g* and pivotal screw *P*, and with the spirit-level-carrying bar *A*, arched standard *B*, telescope *I*, and the adjusting-screws *K K* and *N' N'*, arranged as set forth.
2. The circular stand *R*, provided with the circular flange, divided arc, central pivot, centralizing-pointer, and adjustable legs, arranged and for use substantially as set forth.

JOHN W. HARMON.
